UNITED STATES PATENT OFFICE.

HARRY E. COLE, OF AKRON, OHIO, ASSIGNOR TO THE COLE FOLDING BOX COMPANY,
OF AKRON, OHIO, A CORPORATION OF OHIO.

FOLDING BOX.

Application filed March 30, 1926. Serial No. 98,473.

This invention relates to folding boxes or shipping containers.

The general object of the invention is to provide an improved double side wall box blank construction of that type having one closed end and which is adapted to be easily and quickly folded into a strong shipping container.

In particular the invention contemplates in a box of this type the combination with side walls on the bottom and top, of foldable connecting gussets between the adjacent ends of the side walls and connected to the closed end; of flaps on the free ends of opposite side walls adapted to be interlocked with each other to connect the opposite side walls securely together and to form a strong closure for the open end; and the combination with the bottom of the box of an additional closure for the open end of the box with a "tuck-in" tab for holding the top and bottom of the box together.

The foregoing and other objects are obtained by the box illustrated in the accompanying drawings and described below. It is to be understood that the invention is not limited to the specific form thereof shown and described.

Of the accompanying drawings:

Figure 1 is a plan of the box blank; Figure 2 is a perspective illustrating the blank partly folded; Figures 3 and 4 are respectively longitudinal and transverse sections through the box during a further stage of the folding process;

Figure 5 is a perspective showing the box after the tabs on the top side wall have been interlocked across the open end; and

Figure 6 is a perspective of the completely folded box.

Referring to the drawings, 1 is the bottom of the box, 2 the top, 3 the closed end and 4 the closure for the open end. These four elements of the finished box are arranged in a line through the center of the blank, the closure 4 carrying a small "tuck-in" tab 5 which is also in line with the four parts just described. At the sides of the bottom 1 are the parallel side walls 6 and at the sides of the top 2 are similar parallel side walls 7 which, for the sake of distinguishing, may be termed the bottom and top side walls respectively.

At the sides of the closed end 3 are lo-

cated the gussets 8 which lie between the side walls 6 and 7 and are preferably scored by crossing diagonal scorings 9 to facilitate the folding of the box. This scoring may be of any preferred form so that the gussets 8 will fold properly. In the form illustrated, there is shown a species of scoring such as covered in my prior Patent No. 1,230,675 of June 19, 1917. The gussets are rectangular in shape, but do not extend quite to the edges of the side walls between which they are located, the outer edges of the gussets thereby not interfering with the folding of the box.

On the free ends of the side walls flaps 10 are provided, these flaps being formed with inner edges 11 cut at outwardly directed angles so as not to interfere with folding operations and formed with notches 12 cut inwardly from the edges of the flaps 10 so that when the side walls are turned upwardly one flap 10 will have a downwardly directed hook-like tab 13 thereon and the opposite flap 10 will have an upwardly directed hook-like tab 14 thereon whereby tabs 13 and 14 may be interlocked as shown at the right ends of Figures 2, 3 and 5.

In folding the box, the first operation is to bring the side walls at right angles to the blank to the position shown in Figure 2 along the lines 20. The flaps 10 on the bottom side walls 6 are then folded inwardly and interlocked as shown. The bottom side walls 6 are now held by the thumbs and second fingers while pressure exerted by the first fingers upon the gussets 8 causes them to fold along the scored lines 9 and brings the top over the bottom of the box, the top side walls enclosing the bottom side walls as shown in Figures 3 and 4. When the top is brought down the flaps 10 extend forwardly of the open end. These are then folded inwardly and interlocked as shown in Figure 5. It is to be noted that the flaps 10 on the bottom interlock in opposite directions across the open end from the flaps 10 on the top, whereby the box is effectively strengthened against a transverse diagonal collapsing action. The closure 4 is finally folded upwardly and tab 5 is tucked into the slit between the outer edges (now the upper edges) of the top side wall flaps 10 and the top 2 thus securing the bottom to the top.

It will be understood that the goods to be packaged are placed on the bottom of the

box when the latter is folded in the condition shown in Figure 2, the remaining folding operations serving completely to enfold the goods in the box.

The box formed in the manner stated is easy and inexpensive to manufacture and will securely hold when in folded condition. The invention is not necessarily limited to the utilization of every feature in a single 10 box, as some of them may be utilized without all of the other features. Accordingly modifications of the invention may be resorted to without departing from the spirit thereof or the scope of the appended claims.

15. What is claimed is:

1. A folded box made from a one-piece blank comprising a sheet of material having defined therein a top, closed end, bottom and a closure for an open end in a line through 20 the center of the sheet, top and bottom side walls laterally of the top and bottom, respectively, gussets between the top and bottom side walls, said gussets being scored so as to fold inwardly, flaps on the free ends 25 of the side walls, and opposite flaps being formed with notches providing interlocking hook-like tabs for connecting the opposite side walls, the tabs on the top side wall flaps interlocking in reverse direction across the 30 open end from the tabs on the bottom side wall flaps, said closure for the open end having a tab thereon adapted to be tucked in between the outer edges of the remote flaps

and the top for connecting the bottom to the top.

2. A folded box made from a one piece blank including a top closed end, bottom and a closure for an open end in a line through the center of the blank, top and bottom side walls laterally of the top and bottom respectively, flaps on the free ends of the side walls at both ends of the blank, opposite flaps being formed with hook-like tabs for connecting the opposite side walls, said tabs interlocking in reverse direction.

3. A folded box made from a one piece blank including a top, closed end, bottom and a closure for an open end having a securing tab on its free end, the above elements being arranged in a line through the 50 center of the blank, top and bottom side walls laterally on the top and bottom respectively, diagonally foldable gussets connecting the top and bottom side walls, and flaps on the free ends of both the top side walls 55 and bottom side walls, said flaps being formed with hook-like tabs adapted to be interengaged to hold the side walls in folded positions, the interengaged flaps of both the top and bottom side walls being adapted to 60 overlap across the open end of the box and to be engaged by the tab on the closure for said end whereby the box is effectively secured in folded position.

HARRY E. COLE.
